VACUUM CAN SEAMER

Arthur G. Hopkins, Maspeth, N. Y., assignor to
 National Can Corporation, New York, N. Y., a
 corporation of Delaware

Application December 14, 1940, Serial No. 370,130

13 Claims. (Cl. 113—14)

This invention relates to can seaming machines, and more particularly to apparatus for completely double-seaming cans under vacuum in a single machine.

The primary object of my invention is to generally improve vacuum can seaming apparatus. Modern vacuum cans are highly vacuumized, so that a dry product, for example coffee, will be pulled completely out of the can unless the cover is held securely and with a fairly tight fit during vacuumization. With liquids, or solids in liquids, there is somewhat less difficulty, as there is less air present in the can, but even then it is important to hold the cover firmly on the can because if some of the content is drawn between the can edge and cover, a defective seam will be produced. The most common prior practice is to seam the can in two distinct and separated operations. In the first operation, performed under atmospheric pressure, the cover is curled about the edge of the can enough to hold the cover securely on the can. The curl is tight enough to prevent vertical movement of the cover, yet is not a real seal because the cover may, for example, be rotated relative to the can. After the can has been put in this condition it is subjected to vacuum, and is then sealed by a final seaming operation.

One primary object of my invention is to simplify the foregoing procedure by eliminating preliminary clinching or curling of the cover, or from a different viewpoint, this object of my invention is to successfully vacuumize and double-seam a can in a single seaming machine having seaming mechanism substantially the same as that commonly used with non-vacuum cans.

A more specific object is to place caps on the filled cans and to hold the same firmly and reasonably tightly on the can for vacuumizing prior to seaming. Another more specific object is to dispense with the need for an extra turret or other such means to produce a special time delay for vacuumizing the can. With a vacuum chamber it is common practice to use rotary inlet and discharge turrets or so-called "valves," and in accordance with a feature and object of my invention, the caps are held on the cans (and the cans are vacuumized) during their passage through the inlet valve.

A further object is not to interfere with the normal seaming machine parts, particularly the chuck for engaging and holding the cap, and accordingly, the means for holding the cap on the can during passage through the inlet valve, preferably comprise jaws which engage only the side edges of the cap. It is difficult to supply the

caps to such jaws tangentially, and in accordance with a further feature and object of the invention, the caps are delivered to the jaws by means of a vertically reciprocable elevator which receives the caps at a higher elevation and lowers the same to the jaws as the jaws sweep past the elevator.

Still another object is to afford time for this delivery of caps by the elevator in registration with the cans, and for this purpose, the caps are fed to the elevator somewhat ahead of the cans, both being moved by a transfer turret. In accordance with the present invention, the cans and caps are fed by separate fingers which are so designed that they may be mounted on a single spindle and moved by a single cam follower, yet the cap is advanced relative to the can in order to provide time for descent of the elevator.

The transfer turret also carries plungers with tamping plates for tamping the contents well into the can prior to application of the cap. The tamping plungers are very important when dealing with cans having solids, but are not necessary and are undesirable when dealing with cans having only liquids without solids. A feature of the present invention is a special mounting whereby the tamping plungers, together with their bushings and cam followers, may all be readily bodily removed when not needed.

Other objects of the invention center about the rotary valve for the vacuum seaming chamber. Various suggestions have been made for using spring-pressed or yieldable sealing plates in engagement with the valve turret, but I find it advantageous to rotate the valve with a fixed clearance between rigid sealing plates, the seal being completed by the use of a continuous oil film or seal between the moving parts. Another object is to adapt the valve for use with cans of different diameter, and for this purpose the outer walls of the valve are provided with inner lining walls or sealing walls which may be removed and replaced to accommodate a change in can and turret diameter. Another object is to accommodate the cap, which at this time is larger in diameter than the can. The sealing plate is cut away or stepped to receive the edge of the cap, and appropriate filling strips are provided to prevent loss of vacuum through the resulting step.

Other objects center about the seaming mechanism. This mechanism is of a known successful type employing planetary gearing at the top of the machine for controlling the necessary movements of the turret, the individual seaming heads, and the seaming rollers. Additional gear-

ing is provided at the bottom of the machine for synchronously driving the other turrets associated with the seaming turret. Serious lubricating difficulty might arise if the gearing were placed under vacuum, as the oil would be drawn away. An object of the present invention is to overcome this difficulty, which I do by providing annular seals to isolate the center region of the seaming machine, the upper seal being located below the upper gearing of the machine, though preferably above the seaming heads, and the lower seal being provided above the lower gearing and below the can tables. In this way there is no interference with normal functioning of the seaming mechanism, nor with the delivery and discharge of cans to and from the same, the entire seaming operation being carried out under vacuum, yet the gearing operates under atmospheric pressure.

To the accomplishment of the foregoing and other objects which will hereinafter appear, my invention consists in the vacuum seaming machine elements and their relation one to the other, as hereinafter are more particularly described in the specification and sought to be defined in the claims. The specification is accompanied by drawings, in which:

Fig. 1 is a horizontal section showing the seaming machine in plan;

Fig. 2 is a schematic diagram explanatory of the gearing for driving the turrets associated with the main seaming turret;

Fig. 3 is a vertical section through the indexing turret, taken approximately in the plane of the line 3—3 of Fig. 1;

Fig. 23 is a similar view of a modified elevator having yieldable spring-pressed cap supporting fingers;

Fig. 24 is a side elevation of the same;

Fig. 25 is a partially sectioned similar view illustrating a modification having cam-controlled cap supporting fingers, and is taken approximately in the plane of the line 25—25 of Fig. 26; and

Fig. 26 is a partially sectioned side elevation of the double cam control mechanism for the elevator of Fig. 25, this view being taken in substantially the same plane as Fig. 21 (i. e., 21—21 of Fig. 9).

Referring to the drawings, and more particularly to Fig. 1, the complete seaming apparatus 40 comprises an indexing turret generally designated I, which supplies filled but uncovered cans in properly spaced relation to a transfer turret generally designated T. The latter is provided with plates, not shown in Fig. 1, but indicated at P in Figs. 4 and 9, for tamping the can contents, and is also provided with cam controlled fingers F. The caps are supplied from a suitable magazine M by conventional cover feed mechanism generally designated C. The fingers F of transfer turret T move the cans and the caps to the inlet valve V. The caps are received by an elevator, not shown in Fig. 1, but generally designated E in Figs. 9 and 14—20. The elevator delivers the caps downwardly to depressor jaws J carried by the turret of valve V, said jaws holding the cap at its edge and depressing the same against the top of the can as the can moves through the valve V and before it is subjected to the high vacuum in the enclosed vacuum chamber of the main seaming turret S. The cans are subjected to first and second seaming operations in the turret S, and are discharged by wheel W and discharge valve D.

65 The indexing turret

Considering the arrangement in greater detail, and referring first to Figs. 1 and 3, the filled cans 12 are supplied along a track 14 leading to the indexing turret I. This may be of conventional character, and comprises a smooth stationary plate 16 provided with a spring-pressed guide rail 18 for holding the cans in engagement with the indexing disc 20, the latter being secured to shaft 22 through appropriate adjusting slots and screws 24.

The disc 16 is cut away at 26 to mate with the periphery of the transfer turret T, and the cans are guided into the pockets of the transfer turret by the normal action of the indexing wheel aided by a suitable outside guide rail 28.

The transfer turret

The transfer turret T may be described with reference to Figs. 1 and 4. It comprises a turret body 30 mounted on and rotated by a shaft 32. A tamping plate P is disposed over each of the turret pockets, said plate being carried at the outer end of an arm 34 mounted at the upper end of a non-circular, in this case square, plunger 36. The plunger 36 is reciprocable in a bushing 38, said bushing being cylindrical at its upper and lower ends, though the intermediate part may be cut away, as indicated at 40, to save weight. Plunger 36 carries a cam follower roller 42 at its lower end, said roller projecting radially inwardly into a cam groove 44 on the periphery of a stationarily mounted cylindrical cam 46. It will be evident that as the turret rotates, the tamping plates P will be lowered from the position shown at the right-hand side of Fig. 4, to a position as shown at the left-hand side, thus depressing the contents into the can.

When dealing with liquids, it is unnecessary and undesirable to employ the tamping plates P, and in such case, they may be removed by releasing the bolts 48 holding the flange 50 or the top of the bushing. However, withdrawal of the plunger assembly would be prevented by the roller 42 received in the cam groove 44, and to overcome this difficulty, the plunger 36 is preferably eccentrically mounted in the bushing 38. Thus, by rotating the arm 34 approximately ninety degrees after releasing the bolts 48, the roller 42 is turned out from the cam groove to a position clear of the cam, as will be seen by comparison of Figs. 4a and 4b, whereupon the entire assembly is readily lifted upwardly out of the turret.

The transfer turret T is also provided with a pair of fingers for each can pocket. There is a lower finger 52 for moving the can and an upper finger 54 for moving the cap which is to be placed on the can. Both fingers are mounted on a single spindle 56 which is provided at its lower end with a cam follower arm 58 carrying a roller 60 which runs in a cam track 62 formed on the upper surface of a large stationary plate 64.

The action of the fingers is described in greater detail later.

The cap feed mechanism

The cap feeding mechanism C is shown in Figs. 1 and 5. It may be of conventional character, and requires no detailed description. The caps are stacked in a magazine M, the stack being supported by a conventional reciprocable knife generally designated 66. The knife is reciprocated by a slide 68 connected by pin 70 and connecting rod 72 to a crank pin 74 on a crank disc 76. The crank disc is carried at the upper end of a rotating shaft 78. This in turn is driven by a first intermediate shaft 80 through a suitable pawl 82 which may on occasion be released under the control of suitable "no cam—no cap" linkage 84. Shaft 80 is driven by a second intermediate shaft 86 through a coupling 87. Shaft 86 is driven by a lower shaft 88 through appropriate bevel gearing 90. A ball clutch 92 may, if desired, be inserted between shafts 88 and 86, with a suitable limit switch 94 to cut out the driving power of the entire machine in the event of a jam.

The separating edge 96 of knife 66 separates the lowermost cap from the stack during return or leftward return reciprocation of the knife. This cap is then delivered from beneath the magazine to a suitable marker or printing station 98 by a first pusher 100. Upon the next reciprocation of the slide, the marked cap is pushed by a second pusher 102 to a second station, where it is picked up by the upper feed fingers of the transfer turret. Return movement of the caps is prevented at the first station by check fingers 104, and at the second station by check fingers 106. The marker has been omitted in Fig. 5, but is clearly shown at 108 in Fig. 1. A counter 110 (Fig. 5) may be provided to keep count of the number of cans seamed in the machine.

The rotary inlet valve

The inlet valve V is shown in Figs. 1, 6, and 9 through 12, referring to which figures, it may be explained that the turret body 112 is carried on a driving shaft 114. It moves within side walls 116 formed integrally with bottom wall 118, and is closed at the top by a cover plate 120. The walls 116 are lined by means of removable sealing plates 122. These may be changed to accommodate cans of different diameter, without necessitating a change of the main outside walls of the valve housing. The lining plates 122 are fixedly mounted on walls 116, which in turn are rigidly or fixedly secured to the main vacuum seaming chamber. The turret body 112 is accurately finished to a diameter which fits the sealing plates accurately, but with a small clearance, say, several thousandths of an inch. The desired vacuum seal is maintained by introducing a viscous oil film between the relatively moving surfaces. This may be done in any suitable manner, as by the use of a plurality of sight feed oil cups 124. The space 126 (Fig. 6) between the wall 116 and the lining plates is, of course, sealed at either or both ends, as will be seen at 128 in Fig. 1.

The valve turret 112 carries the depressor jaws J for holding a cap firmly on the can as it is being vacuumized. The jaws are controlled by cam mechanism which may be described with reference to Figs. 6, 11 and 12. The leading jaw 130 is mounted at the upper end of a pin 132. The trailing jaw 134 is mounted at the upper end of a pin 136. The pins 132 and 136 are connected for equal opposite movement, as for example by means of arms 138 and 140 connected at a common center 142. If desired, the arm 138 may be provided with a pin carrying a block 144, which block is slidably received in a mating slot in arm 140, thus compensating for angularity. It is convenient to form the arm 138 integrally with the jaw 130, and to form the arm 140 integrally with the jaw 134, as shown.

One of the pins, in this case the pin 132, is provided with an internally received spindle 168, which in turn is provided at its lower end with a cam follower arm 146 carrying a roller 148. Referring to Fig. 12a, it will be seen that counter-bored or sleeve-like pin 132 is prevented from rotating relative to the spindle 168 by means of a suitable axially extending key 170. Referring now to Fig. 6, the roller 148 runs in a cam groove 150 formed on the upper surface of a stationarily mounted cam plate 152. It will be evident that with this construction as so far described, the jaws may be opened or closed at appropriate times as the turret revolves relative to the stationary cam 152.

It is also necessary to raise and lower the jaws,

and for this purpose, the pins 132 and 136 (Fig. 12) pass through a block 154 in which they are freely rotatable. However, the pins are prevented from axial movement relative to the block by means of peripheral grooves 156 receiving the inner ends of keys 158. The block 154 carries a cam follower roller 160 which runs in a cam groove 162. In Fig. 6 it will be seen that it is convenient to form the cam groove 162 on the adjacent faces of circular plates 164 and 166, said plates forming a cylindrical cam which is stationarily mounted within the rotating turret 112. It will be evident that as the turret revolves, the jaws are raised and lowered under control of the cam, the vertical movement being accommodated by the sliding relation between the pin 132 and its internally received spindle 168. It will also be evident that by the use of the two cam movements described, a four-way motion of the jaws is readily obtainable, with the opening and closing movement entirely independent of the rising and falling movement.

The caps are larger in diameter than the cans. It is desirable to confine the cans against outward movement, thus determining the radius of the valve and sealing plates, but it is then desirable to cut away or step the sealing plates near the upper edge thereof, as is indicated at 172 (Fig. 6) in order to accommodate the caps. Of course, leakage through the resulting passage must be prevented, and this may be done by stepping the valve turret outwardly, as is indicated at 174 in Fig. 6a, or by stepping the valve outwardly for only a small distance, as is indicated at 176 in Fig. 6b, the remaining space being filled by a stationary wear strip 178. In the latter case, however, it is convenient to provide a greater thickness for the wear strip by cutting away the valve turret as well as the side wall, thus leading to a construction as is indicated in Fig. 6, in which the turret is flanged outwardly at 180 and is stepped inwardly at 182, the resulting space being filled by a stationary wear strip 184. When a wear strip is used, the wear strip overlies the outer edge of the cap, and the wear strip may be so proportioned as to help bear downwardly on the cap and to insure good seating of the same on the can. In such case, however, it is evident that the wear strip, which is stationarily mounted on the top plate 120 of the valve assembly, should be so located that it is reached by the caps only after they have been depressed by the jaws, for otherwise there would be interference between the caps and the wear strip. This problem arises only, of course, on the incoming side of the valve, there being no caps in the outgoing side. The outer edge of the cap then occupies a space represented by the outward step 180 on the turret, but this step does not interfere with the cap, because it exists only on the parts of the turret between the can pockets, the turret being wholly cut away at the can pockets.

The elevator and associated mechanism

The elevator E is mounted on top of the valve, and is driven by the valve shaft 114, or more specifically, by a cam mounted on the upper end of said shaft. Referring to Figs. 9 and 21, the turret shaft 114 carries a cylindrical cam 186 on its exposed upper end. This operates a cam roller 188 carried by an arm 190 which is mounted on a pin 192 supported in a stationary bearing 194 the base 196 of which is secured to the top of the valve housing. The opposite end of pin 192 carries an arm 198, the forward end of which

is pivotally connected to a bearing 200 formed at the upper end of a plate-like elevator 202 which is vertically reciprocable in bearings 204. It will be evident that rotation of cam 186 may be used to produce vertical movement of the elevator 202, and that the cam 186 preferably has five movements for each rotation, so that the elevator will be depressed once for each cam (there being five pockets to a turret).

Referring now to Fig. 22, the elevator plate 202 is formed with a pair of support fingers 206 at its lower end. These are so spaced as to receive and support a cap delivered thereto by the transfer turret. The support fingers 206 are disposed at the ends of a diameter approximately perpendicular to the points where the jaws of the valve grip the cover, and there is accordingly no conflict therebetween. The jaw arms are shaped downwardly enough to clear the lower ends of the support fingers, as will be clear from inspection of Fig. 18. The direction of movement of the jaws is such as to slide the cover from between the support fingers.

If desired, the support fingers may be spring-pressed in order to grip the covers with a frictional grip. Such an arrangement is illustrated in Figs. 23 and 24, referring to which it will be seen that the elevator plate 208 is provided with support fingers 210 pivoted at 212 and acted upon by compression springs at 214. It will be evident that this arrangement will operate in the same manner as the elevator shown in Fig. 22, except that a better grip on the cap is assured.

If desired, the support fingers may be spring-pressed, yet positively released by cam means when being carried away by the jaws. Such an arrangement is shown in Figs. 25 and 26, referring to which it will be seen that the elevator plate 216 is provided with cap support fingers 218 pivoted at 220 and normally acted upon by compression springs 222. The upper ends of the fingers are biased to form wedge-like camming surfaces 224 which may be acted upon by mating sloping ends on vertically reciprocable rods 226. The upper ends of these rods are connected to the outer ends of levers 228, said levers being fulcrumed at 230, and having ball-shaped inner ends 232 which are received in a yoke 234 formed at one end of an arm 236 (Fig. 26) which is mounted above and extends collaterally of the arm 238. Arm 238 corresponds to the arm 198 shown in Fig. 21, and is pivoted at 240 and actuated by cam follower roller 242 just as was previously described. Arm 236 is similarly pivoted at 244 and acted upon by a cam follower roller 246. The cylindrical cam 248 is provided with two cam grooves 250 and 252. The groove 250 is the regular cam for reciprocating the elevator 216. The cam 252 has a generally similar cam track so that for the most part, the linkage controlling the jaws follows the elevator without relative movement. However, by providing a slight departure in the tracks at any desired point, the finger-controlling linkage may be moved relative to the elevator, and downward movement of the rods 226 will obviously release the cap support fingers 218. Such a release is preferably provided at the instant when the jaws of the valve have seized the cap and are moving the same from between the support fingers.

In order to bring the caps in registry over the cans in the valve, the elevator should receive and lower each cap as its mating can body is moved into the valve pocket. For this purpose, the cap is preferably fed to the elevator somewhat

ahead of the can body. For purposes of design simplicity, the timing of the machine may be made such that the caps are supplied to the transfer turret substantially synchronously with the cans, the caps then being accelerated somewhat as they are moved by the transfer turret to the elevator. Again for the sake of simplicity, it is desirable that the fingers on the transfer turret moving the can and the cap, be moved together by a single cam. This is the construction which has already been described in connection with Fig. 4 showing the cap-moving finger 54 on the same spindle 56 as the can-moving finger 52. The manner in which the desired gain or acceleration is obtained, will be clear from inspection of Fig. 10, in which it will be seen that finger 54 is displaced or advanced relative to finger 52, thus delivering the cap 256 ahead of the can 258. The latter is being received in valve turret pocket 260, while the cover is received in the elevator, not shown in Fig. 10. The valve turret rotates as the elevator descends, thus bringing the jaws 262 (Fig. 10) around to proper position to receive cover 256 from the elevator. The cap is first delivered by the cap feed mechanism to the broken line position 256', where it is engaged by the finger 54'. The finger 52' need not yet engage the can 258', the latter being moved by transfer turret pocket 264. As the transfer turret revolves the cap is moved to position 256'' when the finger is in position 54'' and the can is moved to position 258'' by finger 52''. The guides are omitted in Fig. 10, but Fig. 9 clearly shows the spaced guides or tracks 270 for the cover, said tracks leading from the cover feed mechanism C to the elevator E.

The manner in which the upper fingers 54 avoid interference with the cover guide track 270, will be clear from inspection of Fig. 13, in which it will be seen that the finger 54 underlies the track 270, and is provided with an upward projection 272 for engaging the cap. The can body may be guided by an outside guide 274 and is moved by the finger 52. The tracks 270 may be connected at spaced points by one or more top braces 276, said braces clearing the path of travel of the caps.

Referring to Fig. 9, there is no interference between the fingers and the elevator E, because the fingers begin to move inwardly or toward the left as seen in Fig. 9, as soon as the cap is in the support fingers of the elevator, and this inward movement of the feed finger 54 may be so regulated by the shape of the controlling cam, that the finger will clear the elevator without mutual interference. The guide 270, of course, terminates at a point 271 which affords adequate clearance for the desired retraction of finger 54.

The action of the valve jaws in taking the cap from the elevator and pressing it on the can, will be clear from inspection of Figs. 14 through 20. In Fig. 14, the valve pocket 278 and the jaws are still empty, these parts moving with the valve toward the right relative to the stationary elevator E. The latter is also empty, the cap not having been delivered to the elevator as yet.

In Fig. 15 the valve has moved further toward the right, and has received a can 282. At the same time, the elevator has received a cap 284. The elevator and cap are above the valve turret, and do not interfere with its movement.

In Fig. 16 the turret has moved further toward the right, and the elevator has descended

into the turret pocket to the level of the jaws, which at this time are in their raised position.

In Fig. 17 the jaws have closed to grip the cover, the cover at this time being disposed directly over the can.

In Fig. 19 the turret has continued its movement toward the right, causing the jaws to carry the cap 284 out of the support fingers of the elevator E, the latter remaining in depressed position.

The manner in which the jaws clear the lower ends of the elevator will be apparent from inspection of Fig. 18, the jaw arms being downwardly offset relative to the jaws, for clearance at the point 286.

In Fig. 20 the turret has moved further toward the right relative to the elevator E. The elevator has been raised in time to clear the turret pocket, thus avoiding interference with continued movement of the turret. At the same time, the jaws J have descended to press the cap 284 against the upper edge of the can 282. The pressure exerted is sufficient to prevent any escape of contents from the can, but, of course, there is no effective sealing action such as would prevent extraction of air from the can. This is so, because the cap has not been seamed to the can body, and there is accordingly no effective seal such as would withstand the high degree of vacuum maintained in the vacuum seaming chamber.

On inspection of Fig. 1, it will be recognized that there is adequate time for the jaws to depress the cover to the can before the valve pocket is exposed to the suction of the vacuumizing chamber.

The seaming turret

The seaming turret S is best shown in Fig. 8. It may be a multiple-spindle turret of any suitable type, but that here shown employs planetary gearing of the character disclosed in my prior Patent No. 1,989,518, issued January 29, 1935. Briefly, power is applied to pulley 288, and its shaft 290 turns the vertical drive shaft 292 through a worm 294 and mating gear. Shaft 292 turns a sun gear 296 meshing with planet gears 298 which in turn mesh with a stationary ring gear 300. Planet gears 298 revolve about shaft 292 and carry the seaming turret with them. Planet gears 302 rotate with the planet gears 298, and mesh with a ring gear 304 which is fixed on the turret and with a sun gear 306 which in turn rotates the seaming head 308 at high speed. A similar set of planetary gearing of slightly different ratio is provided (the planet gear of which is indicated at 310) in order to produce a slightly different high speed rotation, resulting in a very slow relative movement of a cam 312, thus causing the desired inward and outward movement of the first and second sets of seaming rolls, one of which is indicated at 314. The seaming heads are not vertically reciprocable. The cans are carried on vertically reciprocable can tables 316, these being raised and lowered by a stationary cam 318. The cap is held tightly on the can body during the seaming operation by means of a chuck 320. A knock-out 322 is carried at the lower end of a rod 324, the upper end of which cooperates with the stationary cam 326.

The action is conventional in that the cans are transferred from the valve V (Fig. 1) to the turrets as the valve pocket and seaming station come to a common center. The jaws J of the

valve open and move out of the way in time to avoid interference with the rapidly spinning seaming rolls, which at this time are above the jaws because the can table 316 (Fig. 8) is in lowered position. The can table then rises, thus causing the chuck 320 to hold the cap on the can, following which the first and then the second sets of rolls move inwardly to seam the can. The can table again descends, following which the sealed cans are guided from the turret by guide rails 328 and 330 (Figs. 1 and 8), the cans being moved by a pocket of wheel W and being thereby transferred into the path of action of the discharge valve D. This valve employs an oil seal, as previously described, and may be provided with discharge fingers 332 mounted on spindles 334 carrying at their lower ends cam follower arms 336 (Fig. 8), the rollers 338 of which run in a stationary cam groove 340.

The wheel W is mounted at the upper end of a shaft 342, the lower end of which is provided with a bevel gear 344. The discharge valve D is mounted on a shaft 346 coupled at 348 to an intermediate shaft 350 which in turn is connected to a lower shaft 352 by means of a ball clutch 354, which in turn may have associated with it an electric limit switch 356 for stopping the driving motor of the machine in the event of a jam. Also, shaft 352 carries a bevel gear 358. The shafts 342 and 352 are driven by vertical drive shaft 292 through bevel gears 360, 362, 364, 344, 366, 368, and 358, with their connecting horizontal shafts 386 and 388.

It will be seen from the foregoing description, that there is a substantial number of sets of planetary gearing in the upper part of the machine, and substantial amount of bevel gearing in the lower part of the machine. All of this gearing must be thoroughly lubricated and may even run in an oil bath. It is accordingly desirable to keep the upper and lower parts of the machine under atmospheric pressure instead of under vacuum, for otherwise the exhaust suction would remove all of the lubricant. I accordingly connect the main section or exhaust pipe 370 to the seaming chamber at an intermediate point 372. I provide a main upper seal 374 at a point below the planetary gearing in the upper part of the machine, but above the seaming heads. I provide a main lower seal 376 at a point above the gearing in the lower part of the machine, but below the can tables. It will thus be evident that the can being seamed is under vacuum throughout its treatment and movements within the seaming chamber, yet the lubricated gearing and main bearings may be under atmospheric pressure. The vacuum being maintained may be observed on a suitable gauge such as that indicated at 378. If desired, an additional gauge may be provided at the top of the machine at 380, as an additional check on the efficiency of the seals at 374 and 376, for any failure at the seals will tend to produce a less than atmospheric reading at gauge 380.

The seal at 374 is produced by a large-diameter floating ring 382 preferably made of a suitable bearing material such as bronze. It is generally triangular in shape, providing a sloping lower surface which rests on a mating sloping surface on a ring 384 which is secured to and rotates with the turret. It will be evident that the ring will initially tend to seal the chamber at the point 374 due to the attraction of gravity, and that this seal is thereafter maintained even more effectively by the very existence of a vac-

uum beneath the ring 382. The ring may be either a one-piece ring or a segmental ring with overlapped or interleaved ends.

The seal at the point 376 is a plain horizontal surface, but is effective because the thrust bearings supporting the turret may be so adjusted as to leave any desired residual pressure at the seal 376, that is, a part of the weight of the turret may be used to make the seal effective.

10

The drive for the turrets

The manner in which the turrets are driven is schematically illustrated in Fig. 2. It has already been explained in connection with Fig. 8, 15 how the vertical shaft 292 of the seaming turret S is geared through appropriate bevel gearing to the shaft 342 of the wheel W and the shaft 346 of the discharge valve D, the coupling taking place through short horizontal shafts 386 and 388. Similarly, the vertical shaft of the seaming turret S is geared by appropriate bevel gearing and a horizontal shaft 390, to the vertical shaft 114 of the inlet valve. Referring to Fig. 7, shaft 390 carries gear 392 meshing with gear 394 mounted at the lower end of a shaft 396 which is coupled to an intermediate shaft 398 by means of a ball clutch 400. A limit switch 402 may, if desired, be associated with the ball clutch to cut off power to the driving motor of the machine 20 in the event of a jam. Intermediate shaft 398 is coupled to the valve shaft 114 by means of a suitable coupling generally designated 404 in Fig. 6.

The bevel gear 394 at the lower end of shaft 35 396 also meshes with a pinion 406 carried on a horizontal shaft 408.

Reverting to Fig. 2, the shaft 408 is geared to the upright shaft 32 of the transfer turret. Referring now to Fig. 4, the shaft 408 carries a bevel pinion 410 meshing with a bevel pinion 412 mounted on a lower shaft 414. Shaft 414 is connected to shaft 32 by means of a suitable coupling generally designated 416.

Reverting to Fig. 2, the vertical shafts of the 45 transfer turret are connected by suitable bevel gearing and a horizontal shaft 418 to the vertical shaft 22 of the indexing turret, and referring to Fig. 3, it will be seen that shaft 418 carries a bevel pinion 420 meshing with the bevel gear 422 carried at the lower end of shaft 22 of the indexing turret.

Reverting to Fig. 2, the vertical driving shaft 88 of the cap feeding mechanism is driven by the transfer turret through appropriate bevel 55 gearing and a horizontal shaft 424. Referring to Fig. 5, the shaft 424 carries a bevel gear which meshes with a pinion on shaft 88. It will be noted that in this case, a step-up ratio is used, the reason for this being that the cap feeding 60 mechanism must rotate once for each can, or five times as fast as the turrets having five pockets. It will be understood that the bevel gear ratios for the wheel W (Fig. 1), which has only three pockets, and for the discharge valve 65 D, which has four pockets, are appropriately modified for proper synchronous movement.

In connection with some of the turrets, reference has been made to the use of a separable 70 coupling between a lower and upper shaft portion. These are intended to facilitate servicing and accessibility by permitting certain of the turrets to be swung out of the way of others. Specifically, the transfer turret T (Fig. 1) may be swung counterclockwise about the indexing turret, its weight resting on stationary rails 430.

The can feed mechanism C may be swung clockwise about a support shaft 432 (Figs. 1 and 5). This clears the way for opening of the inlet valve V, which may be swung away from the seaming chamber about shaft 434. Similarly, the discharge valve D may be swung away from the seaming chamber about a support shaft 436.

Operation

It is believed that the construction and operation of my improved vacuum seaming machine will be apparent from the foregoing detailed description thereof. The filled can bodies move along track 14 to indexing turret I, which properly spaces the same and feeds the same to the transfer turret T. This carries the can bodies around to the inlet valve V. The can bodies are first moved by the pockets of the transfer turret, but toward the end are moved and controlled by the fingers 52 which move the same into the pockets of the valve turret. The caps are fed to the transfer turret, or more exactly, to the starting end of a special guide track. The caps are moved along the track by the upper fingers 54 of the transfer turret, and are delivered to the elevator E somewhat ahead of the arrival of the can bodies and the valve pocket. The elevator descends, carrying the cap down to the level of the valve jaws, which at this time are in raised position. The jaws close on the cap and move the same out of the elevator, which thereupon rises to clear the approaching parts of the valve turret. The jaws then descend and hold the cap firmly on the top of the can as the can and cap move through the valve. They are so held when the valve pocket is first exposed to the seaming chamber, thus guarding against any loss or disturbance of the can contents as a can is evacuated. The can and cover are delivered to a can table of the seaming turret, said table being in lowered position. As the seaming turret revolves, the can is raised until the cap is held by the chuck, and its periphery is subjected to first and second seaming operations by means of first and second seaming rollers, all in a manner which is already common and conventional with non-vacuum cans. The seamed cans are moved out of the seaming turret by means of the wheel W, and are discharged from the vacuum chamber by means of the discharge valve D, which, of course, leads to a suitable discharge track, not shown in the drawing.

Some of the advantages of the present seaming apparatus which will be apparent to those skilled in the art, are as follows: The entire seaming operation takes place in a single machine just as is done with non-vacuum cans. No preliminary curling of the cover to hold the same on the can is needed, for the cover is held down on the can during vacuumization by the valve-carried jaws. The vacuumization takes place as the cans move through the valve, and no special turret or time delay is required. The valves are sealed by an oil film while maintaining a desired clearance between the turret and the valve walls. The vacuum seals within the seaming chamber itself are so located as not to subject the gearing to vacuum, with consequent lubrication problems.

It will be apparent that while I have shown and described my invention in a preferred form, many changes and modifications may be made in the structure disclosed, without departing from the spirit of the invention as sought to be defined in the following claims.

I claim:

1. Vacuum-seaming apparatus comprising a pocketed transfer turret, a rotary vacuum valve adjacent said turret, means to supply cans to said transfer turret, means to supply caps to said transfer turret for ejecting cans from said transfer turret to said rotary valve, means on said transfer turret for moving the caps to said valve, cam-operated means at said valve for receiving and positively controllably lowering the caps toward the cans a predetermined desired amount, and a cam so arranged as to operate said cam-operated means positively over a desired range of movement.

2. Vacuum-seaming apparatus comprising a pocketed transfer turret, a rotary vacuum valve adjacent said turret, means to supply cans to said transfer turret, means to supply caps to said transfer turret, cam-controlled fingers on said transfer turret for ejecting cans from said transfer turret to said rotary valve, cam-controlled fingers on said transfer turret for moving the caps to said valve, said fingers moving the caps ahead of the cans, cam-operated means at said valve for receiving and positively controllably lowering the caps toward the cans a predetermined desired amount, and a cam so arranged as to operate said cam-operated means positively over a desired range of movement, the movement of the caps ahead of the cans affording time for lowering of the caps toward the cans.

3. A seaming machine comprising a pocketed transfer turret, a rotary vacuum valve adjacent said turret, means to supply cans to said transfer turret, means to supply caps to said transfer turret, fingers on said transfer turret for ejecting cans from said transfer turret to said rotary valve, fingers on said transfer turret for moving caps to said valve, a single cam for simultaneously moving each pair of can and cap moving fingers, said fingers being relatively different so that the caps move ahead of the cans, cam-operated means at said valve for receiving and positively controllably lowering the caps toward the cans a predetermined desired amount, and a cam so arranged as to operate said cam-operated means positively over a desired range of movement, the movement of the caps ahead of the cans affording time for lowering of the caps toward the cans.

4. Vacuum-seaming apparatus comprising a transfer turret, a rotary vacuum valve adjacent said turret, a stationarily located vertically reciprocable cap-lowering device at the inlet side of said valve, stationary means reciprocably supporting said device, means to supply cans to the transfer turret, means to supply caps to the transfer turret, means carried by said turret for transferring the cans to the valve, and means carried by the turret for feeding the caps ahead of the cans to the cap-lowering device, thereby affording time for said cap-lowering device to lower said caps toward said cans while in superposed relations.

5. Vacuum-seaming apparatus comprising a transfer turret, a rotary vacuum valve adjacent said turret, a stationarily located vertically reciprocable cap-lowering device at the inlet side of said valve, stationary means reciprocably supporting said device, means to supply cans to the transfer turret, means to supply caps to the transfer turret, cam-controlled fingers carried by said transfer turret for transferring the cans

to the valve, cam-controlled fingers carried by the transfer turret for feeding the caps ahead of the cans to the cap-lowering device, thereby affording time for said cap-lowering device to lower said caps toward said cans while in superposed relation, means in said valve to hold the caps firmly but not tightly on the cans as the cans come into the vacuumized zone of the apparatus, and driving means for driving the cam-controlled fingers and the cap-lowering devices and the valve 10 all in proper time sequence.

6. Vacuum-seaming apparatus having a vacuumized zone and comprising a transfer turret, a pocketed rotary vacuum valve adjacent said turret, a stationarily located vertically reciprocable cap-lowering device at the entrance to said valve, stationary means reciprocally supporting said device, additional cap-lowering devices mounted on said valve at each pocket for rotation therewith, means to supply cans to the transfer turret, means to supply caps to the transfer turret, means on said transfer turret to feed the cans to the valve and to feed the caps to the first cap-lowering device, mechanism whereby said first cap-lowering device lowers the caps to the second cap-lowering devices, and mechanism whereby the second cap-lowering devices apply the caps to the cans as they move through the valve, and before they reach the vacuumized zone of the apparatus.

7. A vacuum-seaming machine having a vacuumized zone and comprising a rotary inlet vacuum valve, a stationarily located vertically reciprocable cap-lowering device at the entrance to said valves, the said cap-lowering device holding the edge of the cap at the ends of a diameter extending radially of the valve, said rotary inlet valve including sealing walls and a turret having can pockets which are sealed by said sealing walls as the turret rotates, pairs of gripper fingers disposed over each of said pockets, said gripper fingers being arranged to hold a cap at the ends of a diameter extending tangentially of the valve or in the direction of movement of the valve pocket and gripper fingers, whereby said fingers can slide the cap out of the cap-lowering device as the valve rotates, a cam for closing and opening said fingers, and another cam for raising and lowering said fingers, said cams causing said fingers to receive and grip a cap and to apply the same to the can as it moves through the inlet valve, and before they reach the vacuumized zone of the machine.

8. Vacuum seaming apparatus comprising a rotary vacuum valve, said valve including a pocketed turret with top, bottom and peripheral sealing walls, said top and peripheral walls having an inlet opening, a stationarily located vertically reciprocable cap lowering device at the inlet opening of said valve, stationary means reciprocably supporting said device, means to supply cans through the peripheral wall opening into the valve turret, means to supply caps to the cap lowering device at a point above the valve turret, and means to vertically reciprocate the cap lowering device in proper timed relation to the movement of the valve turret in order to feed the caps into the valve turret.

9. Vacuum seaming apparatus comprising a rotary vacuum valve, said valve including a pocketed turret with top, bottom and peripheral sealing walls, said top and peripheral walls having an inlet opening, a stationarily located vertically reciprocable cap lowering device at the inlet opening of said valve, stationary means re-

ciprocably supporting said device, means to supply cans through the peripheral wall opening into the valve turret, means to supply caps to the cap lowering device at a point above the valve turret, said means feeding the caps to the cap lowering device ahead of the feed of the cans to the valve turret, and thereby affording time for said cap lowering device to lower said caps toward said cans while in superposed relation, and means to vertically reciprocate the cap lowering device in proper timed relation to the movement of the valve turret in order to feed the caps into the valve turret.

10. Vacuum seaming apparatus comprising a rotary vacuum valve, said valve including a pocketed turret with top, bottom and peripheral sealing walls, said top and peripheral walls having an inlet opening, a stationarily located vertically reciprocable cap lowering device at the inlet opening of said valve, stationary means reciprocably supporting said device, means to supply cans through the peripheral wall opening into the valve turret, means to supply caps to the cap lowering device at a point above the valve turret, means to vertically reciprocate the cap lowering device in proper timed relation to the movement of the valve turret in order to feed the caps into the valve turret, additional cap lowering devices mounted on said valve at each pocket for rotation therewith, said first cap lowering device 15 serving to lower a cap to that one of the second cap lowering devices which is located in the pocket having the can, and mechanism whereby the second cap lowering device applies the cap to the can as it moves through the valve, said mechanism holding the caps firmly but not tightly on the cans as the cans come into the vacuumized zone of the apparatus.

11. A rotary inlet vacuum valve for a vacuum seaming machine having a seaming turret with a seaming head including a chuck and seaming rolls, said valve serving to transfer cans and caps directly to said seaming turret, said valve including sealing walls and a pocketed turret having 20 pockets which are sealed by said sealing walls as the turret rotates, each of said pockets including a pair of oppositely movable fingers for receiving and gripping a cap at its peripheral edge, the edge grip of said fingers serving to minimize the vertical clearance needed beneath the seaming head chuck and rolls as the valve turret delivers the can and cap to the seaming turret.

12. A rotary inlet vacuum valve for a vacuum seaming machine having a seaming turret with a seaming head including a chuck and seaming rolls, said valve serving to transfer cans and caps directly to said seaming turret, said valve including sealing walls and a pocketed turret having 25 pockets which are sealed by said sealing walls as the turret rotates, each of said pockets including a pair of oppositely movable fingers for receiving and gripping a cap at its peripheral edge, the edge grip of said fingers serving to minimize the vertical clearance needed beneath the seaming head chuck and rolls as the valve turret delivers the can and cap to the seaming turret, means for raising and lowering said fingers, said means causing said fingers to hold the caps firmly but not tightly on the cans as the cans come into the vacuumized zone of the apparatus.

13. A rotary inlet vacuum valve for a vacuum seaming machine having a seaming turret with a seaming head including a chuck and seaming rolls, said valve serving to transfer cans and caps 30

directly to said seaming turret, said valve including sealing walls and a pocketed turret having pockets which are sealed by said sealing walls as the turret rotates, each of said pockets including a pair of oppositely movable fingers for receiving and gripping a cap at its peripheral edge, the edge grip of said fingers serving to minimize the vertical clearance needed beneath the seaming head chuck and rolls as the valve turret delivers the

5 can and cap to the seaming turret, a cam for closing and opening said fingers, a second cam for positively controllably raising and lowering said fingers a predetermined desired amount, said cams causing said fingers to apply the caps to the cans and to hold the caps firmly but not tightly on the cans as the cans come into the vacuumized zone of the apparatus.

ARTHUR G. HOPKINS.
